UNITED STATES PATENT OFFICE.

ROY D. BUELL, OF CHICAGO, ILLINOIS.

EXPLOSION WHISTLE-ALARM.

1,252,232.

Specification of Letters Patent. Patented Jan. 1, 1918.

Application filed December 30, 1914. Serial No. 879,938.

To all whom it may concern:

Be it known that I, ROY D. BUELL, a citizen of the United States, residing at Chicago, in the county of Cook and State of Illinois, have invented certain new and useful Improvements in Explosion Whistle-Alarms, of which the following is a specification, reference being had to the accompanying drawing, forming a part hereof.

10 This invention relates to explosion whistle alarms especially designed for use in connection with internal combustion or explosive engines, and which is particularly applicable for use on automobiles and motor-cycles; but is intended for use, and can be used generally with internal combustion or explosive engines where an alarm is desired or required for any purpose.

20 The objects of the invention are to furnish a whistle alarm of simple construction, which will give, in use, an effective, positive and reliable notice and warning of danger; to mount the whistle on the engine cylinder in direct communication with the explosion 25 chamber; and thus utilize the gas under a high pressure and in a state of combustion for blowing the whistle; thereby obtaining the full benefit of the high pressure of the exploded gas or charge in operating the 30 whistle and giving the alarm; to operate the whistle alarm under conditions and environments adapted for obtaining a pulsating blowing or sounding of the whistle by reason of the varying pressure in the engine cylinder; to positively control the pressure admitted direct from the explosion chamber of the gas in a state of combustion and discharged into the whistle bell for sounding the alarm, by a valve capable of being opened 35 to a greater or less extent as may be required for the nature of the alarm to be given, varying from a low tone to a high startling tone; and to improve the construction and operation of the device as a whole.

40 The invention consists in the features of construction, application, arrangement and combination of parts hereinafter described and claimed:

In the drawings:

50 Figure 1 is a side elevation, showing the device attached in one form to a cylinder of an internal combustion or explosive engine; Fig. 2, a sectional elevation of the casing, showing the controlling valve, its stem and 55 its operating lever in elevation; and Fig. 3, a sectional elevation of a modified form of

casing, showing the controlling valve in section, and its stem and operating lever in elevation and showing also the whistle bell or body in section.

60

The whistle alarm of the present invention has a mounting in the form of a casing, cage, or housing, having a body or wall 1 of a curved elbow shape, as shown in Figs. 1 and 2, with an outlet end 2 and an inlet end 3 and enclosing a vent passage 4, leading from the inlet end to the outlet end. But instead of a curved elbow shaped body or wall 1, the casing, can have a straight body or wall 1, an outlet end 2 in angle relation to the body or wall 1, and an inlet end 3, in line with the body or wall 1, and having a vent passage 4, leading from the inlet end to the outlet end, as shown in Fig. 3. The outlet end 2 in Figs. 1 and 2 has an interior screw thread for attaching the whistle bell or body, while in Fig. 3 the outlet end 2 has an exterior screw thread for attaching the whistle bell or body. The inlet end 3, in both forms of the casing, has an exterior screw thread, for attaching 80 or mounting the whistle alarm on the engine cylinder, as shown in Fig. 1. The casing, in both forms of construction can be made of cast metal, or other material suitable for the purpose.

85

The construction shown in Figs. 1 and 2 has a bracket or base 5, with a lower ear 6 and an upper ear 7, and the under face of the base 5, and the ears 6 and 7 is curved to fit the outer face of the body or wall 1 of the casing. The base 5 is attached to the body 1 by screws 8 or other suitable means; and extending upwardly or outwardly from the head or base 5 is a post, 9, the upper or outer end 10 of which is slotted to receive 90 and support a valve operating lever. The construction shown in Fig. 3 dispenses with the base 5, and has the post 9 with its slotted end 10 cast or formed with the body 1 of the valve casing; and it is evident that the base with its post, 9 could also be cast or 95 formed with the body or wall 1 of the valve casing, instead of being a separate piece of cast metal or other suitable material, attached by screws 8 or otherwise to the body or wall 1 of the valve casing.

100

The inlet end of the eduction or vent passage 4 of the valve casing, has an exterior seating face 11, which co-acts with an inner seating face 12 on a valve 13, and the seating faces 11 and 12 are preferably ground so as to furnish a tight and non,

110

leakable fit between these seating faces, when the valve 13 is seated and prevent any escape of exploded gas around the valve 13, when seated, and also hold the charge against any escape under compression, with the result that the presence of the whistle alarm on the engine cylinder and in direct communication with the compression and explosion chamber in no way interferes with, or destroys, or impairs the operation of the cylinder in receiving, compressing and exploding the charge, and when the valve is held open it will admit but a very small percentage of air during the intake stroke of the engine and the whistle will start to blow or sound the alarm during compression, reaching a maximum of sound when the explosion occurs, which will produce a pulsating tone that is very effective as a warning.

20 The valve stem 14 of the valve 13 passes up or out through a hole 15, formed therefore in the body in wall 1 of the valve casing and in the base 5, which hole fits the valve stem sufficiently close for its wall or face to furnish a guideway by which the valve stem 14 will be held and maintained in a straight line movement in opening and closing the valve 13, thus causing a positive and reliable closing or sealing of the valve so as to be non-leakable against the escape of the exploded gas or the compressed charge or during compression of the charge, when the valve is returned to its seat, after having been opened or unseated to sound the alarm.

25 The projected end of the valve rod or stem 14, in the arrangement shown is encircled by a coil spring 16; one end of the spring rests against the upper face of the bracket or base 5, as in Figs. 1 and 2, or against a flat face on the body or wall 1, as in Fig. 3, and the other end of this spring abuts against a cross pin 17, passing through the end of the valve stem. This spring 16 is a compression spring and has sufficient force to return the valve 13 to its seat and hold it seated after each opening of the valve. The valve 13 is opened, in the arrangement shown, by an L lever having a long arm 18 and mounted on a pin 19 in the slotted end 10 of the post, for its short arm 20 to lie over and in contact or nearly so with the end of the valve stem 14, so that a slight outward movement of the long arm 18 of the L lever will depress the short arm 20 and force the valve stem 14 downward against the force of the compression spring 16 to unseat the valve 13 and allow the gas under full explosive pressure to enter the eduction or vent passage 4 and discharge at the outer end of such passage into the whistle and sound the alarm. The spring 16 with the release of the outward pull on the long arm 18 of the L lever will return the valve stem 14 to its normal position seating the valve 13, and at the same time will return

the L lever to its normal condition ready for the next outward pull. The valve 13, as shown in Fig. 2, has a cross slot 21 in its inner face which can be engaged by a screw driver, or other suitable instrument, by means of which the valve can be turned to grind together the seating faces 11 and 12 and insure a tight non-leakable joint or contact between the seating faces 11 and 12, when the valve is closed as shown in Fig. 2.

70 As shown in Fig. 3, the body or wall 1 of the outer face of the valve casing above the threaded inlet end is formed with a plurality of flat faces 22 for receiving a wrench by means of which the casing can be screwed into the valve cap of the engine cylinder, which is the preferred position for attaching the whistle alarm of the present invention; but the attachment can be otherwise made so long as the mode and point of attachment 80 is one which will furnish free and direct communication between the explosion or compression chamber of the engine cylinder and the eduction or vent passage 4, when the valve 13 is opened or unseated.

85 As shown in Fig. 2, the valve 13 and stem 14 are formed of a single piece, while as shown in Fig. 3 the valve stem 14 has a neck 23 onto which the valve 13 is entered and fixedly secured by upsetting the end of the neck to form a rivet-head, which form of construction permits the valve and stem to be made of different metals, if so desired for any purpose.

90 The outlet end 2 of the valve cage, casing or housing has threaded thereon the whistle alarm, in the arrangement shown. This whistle alarm is preferably made of a single piece of material and of the form shown and can be made of brass or aluminum casting and has a wall or shell 24, inclosing a sound chamber 25 with an escape opening 26 at the base end of the wall. The base end of the wall has a narrow passage or slot 27, formed in the end of wall 28, through which a thin sheet or film of escaping gas or air under engine pressure from the eduction or vent passage 4 is projected into the sound chamber 25 and across the opening 26 producing a resonant, harmonious and agreeable chord. The base end of the whistle alarm terminates in a neck 29 with a chamber 30 outside of the cross wall 28, from which chamber 30 the narrow passage 26 leads. The neck 29 has an interior screw 100 thread for entering the neck onto a connecting nipple or onto the threaded outlet end 2 of the casing or fitting. The neck 29 as shown has a plurality of flat faces 31 to receive a suitable wrench for threading the whistle onto the casing. The whistle alarm can be of a single tone or chime, the chime being produced by three different tones, one of which is quite low and produces a pleasant sound for the whistle. The long 105

arm 18 of the L lever has attached to its extreme end a cord or cable 32, which is extended back and connected to the steering column of an automobile or to some other 5 convenient place on the machine or apparatus with which the explosive engine is used, where the cord can be grasped readily by the driver or operator of the machine or apparatus, for a pull on the cord or cable 10 to cause the L lever to operate and open or unseat the controlling valve 13, as already described.

The whistle alarm can be attached to the engine cylinder in any suitable manner as 15 by entering the neck or inlet end 3 of the cage, or casing, into the valve cap of the cylinder, as shown in Fig. 1.

The gist of the present invention is utilizing under perfect control, the gas under full 20 explosion pressure from the engine cylinder direct in sounding the whistle and giving the alarm and in obtaining the pulsating effect of the whistle blast. It is to be understood that in carrying out the spirit of 25 the invention changes can be made without departing from the end sought provided the structure is maintained within the scope of the appended claim. The whistle instead of 30 having a single chamber 25, with a single opening 26 may have this chamber partitioned off into two or more chambers of different volume, each provided with an opening 26 and with a slot or slit, corresponding 35 to the slot or slit 27, the several chambers being so proportioned in volume as to produce a chime.

What I claim as new and desire to secure by Letters Patent is:

40 An explosion whistle alarm for automobiles comprising an elbow-shaped fitting

adapted to be attached at its lower vertical end to the head of a gas engine cylinder, a valve stem extending through said vertical portion, a valve member on said stem lying at the lower end of said vertical portion and 45 controlling communication between the exhaust passage of the engine and the interior of said fitting, a pivoted valve actuating member secured exteriorly to the fitting and at the upper vertical end thereof and adapted 50 to engage said valve stem and move the same to open the valve, the outer horizontal portion of said fitting being exteriorly threaded to receive the whistle member, said whistle member comprising a hollow body 55 tapering at one end, a horizontal neck extending from said tapering portion and interiorly threaded to mesh with the threads on the horizontal portion of the fitting, the said whistle member continuing outward 60 from said tapered portion in a dome-shaped formation, a cross-wall formed at the inner end of the tapered portion and in front of said neck, said wall being provided with a passage extending diagonally therethrough 65 and off-center therefrom, said body being cut away at its tapered portion to provide a diagonally-disposed opening adjacent said diagonal passage, whereby the gases coming 70 out of said fitting will be forced in a direction to carry them directly across the mouth of the opening to produce a sound, and the dome-shaped portion of said whistle member forming a sounding chamber, substantially as described. 75
